HAND TRUCK

Albion E. Rolland, 1626-A 9th St., Alameda, Calif.

Filed Mar. 16, 1964, Ser. No. 79,032

Term of patent 14 years

(Cl. D14—3)

FIG. 1 is a perspective view of a hand truck showing my new design with the cradle in outwardly extended position;

FIG. 2 is a front perspective view thereof with the cradle in retracted position;

FIG. 3 is a side perspective view thereof with the cradle in a rearwardly extended position;

FIG. 4 is a side perspective view thereof with the chain supports connected to the cradle; and

FIG. 5 is a side perspective view thereof with the cradle in an intermediate position.

I claim:

The ornamental design for a hand truck, substantially as shown.
